CONVEYER

Robert E. Briggs, Columbus, Ohio, assignor to
The Jeffrey Manufacturing Company, a corporation of Ohio

Application November 7, 1940, Serial No. 364,673

9 Claims. (Cl. 198—189)

My invention relates to conveyers particularly of sprocket chain type adapted for use in the pulpwood industry, and one of the objects of the invention is the provision of increased bearing surfaces for a conveyer sprocket chain to increase the life thereof.

A further object of the invention is the provision in a ground supported sprocket chain conveyer, of such a sprocket chain as may have its lower return run efficiently guided along an elongated support instead of over sprocket idlers and thereby enable the overall height of the conveyer to be lowered, thus lessening the height to which material must be manually lifted for entry into the conveyer trough along which the chain conveyer has its conveying path of travel.

Another object of the invention is the provision of block links for sprocket chains provided with bearing surfaces of maximum area for movement over guide plates.

A further object of the invention is the provision of one-piece block links for endless sprocket chains with one side extended into a continuous bearing surface in a single plane for contact through a wide area with a return run guide having upper flat surfaces.

More particularly it is the object of the present invention to extend one side of each of the end barrels of a block link sprocket chain so as to provide flat surfaces in a single plane also extending through flat surfaces of the side bars or side straps connecting the end barrels of the block link.

Other objects of the invention will appear hereinafter, the novel features and combinations being set forth in the appended claims.

In the accompanying drawing,

Fig. 1 is an elevational view partly in section of a conveyer particularly adapted for use in lumber and pulpwood industries for conveying logs and planks;

Fig. 2 is a sectional elevation taken on the line 2—2 of Fig. 1 looking in the direction of the arrows;

Fig. 3 is a plan view of one of the single piece block links;

Fig. 4 is an elevational view of the block link shown in Fig. 3;

Fig. 5 is an enlarged sectional view taken on the line 5—5 of Fig. 3 looking in the direction of the arrows; and

Fig. 6 is an enlarged sectional view similar to Fig. 5 but including a modification.

In the accompanying drawing the invention is embodied in a conveyer which is particularly

adapted for use in the pulpwood industry for conveying logs and planks. The chain 7 is of the endless type comprising the single piece block links 8, 8 and the connecting side bars 9, 9. The block links, as shown in Fig. 3, each comprises end barrels 10, 10 connected by the side straps 11, 11. The end barrels 10, 10 are provided with cylindrical transverse apertures 12, 12 therethrough. Registering with the ends of these apertures are apertures in the side bars 9 to receive the pins or pintles 13, 13. The pins or pintles 13, 13 may each be provided with an enlarged head at one end and a transverse cotter receiving aperture at the other end, or such pins or pintles 13, 13 may each be provided with an enlarged head at one end and be riveted at the other end.

As shown in Fig. 1, the endless sprocket chain 7 is guided around the sprocket 14 mounted on the shaft 15, the ends of which are journaled in a portable frame 16. Suitable apparatus may be provided for driving the chain in the direction of the arrow 116 of Fig. 1.

Substituted for the connecting links 9, or added to the sides thereof, as shown in Fig. 2, at intervals along the chain, as shown in Fig. 1, are pairs of flights or spurs 17, 17 having vertical faces 18, 18 at their leading ends for the purpose of engaging logs or planks to be conveyed along the trough 19. This trough may be composed of side walls 20, 20 inclined downwardly and inwardly as shown in Fig. 2 and connected by the horizontal bottom plate 21. As the chain travels forwardly in the conveying direction indicated by the arrow 116, the bottom of the chain 7 travels over the upper horizontal surface of the bottom plate 21 while the logs or planks lie on the chain between the side walls 20, 20 and between one pair of flights 17, 17 and the next adjacent pair of flights. The pair of flights, 17, 17 should be spaced apart along the chain a sufficient distance to permit the log or plank to lie on the chain throughout its full length.

The return run 7' of the endless sprocket chain 45 is guided over the channel iron support 22, the forward end of which is curved downwardly at 22" as shown in Fig. 1. The upper horizontal surface of the channel iron support is provided with a wear plate 23 preferably of material softer than that of the faces of the chain links which engage the wear plate.

The channel iron support 22 is rigidly connected to the frame 16 in fixed relation therewith. As shown in Fig. 2, the flights 17, 17 straddle the channel iron support 22, and thereby pre-

vent the return run 7' from moving laterally off the wear plate 23. However, the chain is flexible laterally to a certain extent between each pair of flights 17, 17 and the next succeeding pair. The width of each surface 25 is preferably substantially equal to the diameter of the barrel, and is generally at least as wide as the diameter of the pin 13 or pin opening 12.

Pulpwood handling equipment is usually embodied in a large storage system of a modern pulp and paper mill, and the traveling conveyer supporting frame is wheel supported on parallel rails so as to be movable to various positions, each rail being engaged by a pair of wheels. Fig. 2 shows the wheels 31, 31 supporting the frame 16 on the rail diagrammatically shown at 32.

During operation of the conveyer apparatus, the endless chain conveyer is frequently started and stopped, and the driving apparatus is arranged to suddenly start the conveyer chain at full speed. This results in jerking the chain so suddenly that the links between the pairs of flights 17, 17 will be swerved laterally off the wear plate 23 to some extent, with the result that the ordinary chains are unduly worn along certain lines extending transversely of the barrels of the block links inside of the connecting side straps or bars.

Heretofore in pulpwood handling equipment embodying portable conveyer apparatus of the endless chain type, the under or return run has been guided over spaced-apart sprockets. This necessitated such overall height as to raise the sprockets well above the ground level so that they would not gather gritty material from the waste on the ground and carry such gritty material upwardly to the chain causing undue wear of the latter when traveling over such guide sprockets. Furthermore, the sagging lengths of chain between guide sprockets might engage such waste material, gather grit such as sand and cause undue wear of the chain links when engaged by the sprocket teeth.

The overall height of the conveyer apparatus must be sufficient to provide ample space above ground for the guide sprockets each of which is located in the vertical plane of the conveyer chain and below the same. Such overall height makes the work of the attendants arduous because of the height to which the logs or planks must be lifted to introduce them into the conveyer trough.

By the use of my improvements, however, the overall height of the conveyer apparatus including the conveyer trough may be reduced to a minimum. By the elimination of the lower run guiding sprockets and the use instead of the stationary elongated guide 22, the lower run may be brought much nearer the ground level and the height of the frame 16 materially decreased even when wheel supported on spaced rails. Furthermore, the action of guiding sprockets in picking up gritty material and carrying the same to the conveyer chain causing undue wear of the latter is avoided by my improvements.

In fact the wheels 31, 31 may be omitted and the frame 16 mounted in stationary position on the ground, so long as the sprocket 14 is spaced above the ground level even though the flights 17 might brush along gritty material on the ground surface because such flights do not carry gritty substances to the chain.

If gritty substances in the form of dust find their way to the upper surface of the wear plate 23, the wear of the links 8 and the bars 9 on the

wear plate 23 is so widely and evenly distributed that the chain is not injured and a long life is assured. Moreover, such block links 8 as those shown in the accompanying drawing may be made practically dust proof at the pintle connections, thus being well fitted for traveling along and over gritty material on the ground surface.

In order to obtain the wide and even distribution of the wear between the chain 7 and the plate 23, I have provided those sides of the barrels 10, 10 traveling along the wear plate 23, with flat surfaces 25, 25 so as to be in the same plane as the flat surfaces 11', 11' of the side straps or bars 11, 11. It should also be noted that while the barrels 10, 10 between the side straps 11, 11 are semi-cylindrical at 26, 26 on one side of the pintle opening 12, 12, they are in approximate rectangular block formation on the opposite side, as shown in Fig. 4. That is to say, the inner opposing faces 27, 27 of the end barrels 10, 10 are approximately at right angles to the plane which extends through the continuous flat surfaces 25, 25 and 11', 11'. In the same manner, the faces 28, 28 are formed approximately at right angles to the faces 25, 25. By thus providing the flat rectangular opposing faces 27, 27 and the flat rectangular faces 28, 28, the area of each of the flat faces 25, 25, is increased. Consequently when the under run 7' of the chain moves partially off the guide plate 23, there will always remain in contact with such plate 23 a large area of bearing surface including one of the surfaces 25, 25, and this will follow whether the chain moves laterally to one side or the other off the plate 23.

In Figs. 3 and 4 the curved lines 29, 29 illustrate that the lateral surfaces of the side straps 11, 11 are cut away or depressed so as to provide ring bearing surfaces for the connecting side bars 9, 9. The sprocket 14 is of the ordinary type and may be used in connection with an endless sprocket chain embodying my improvements because as shown in section in Fig. 1 the semi-cylindrical surfaces 26, 26 may readily articulate with the teeth of such sprocket 14.

In Fig. 6 I have shown a modification in that in addition to the flat surfaces 25, 25 on one side of the chain, I have provided flat surfaces 25' on the opposite sides of the end barrels which are connected by the side straps 11''. The flat surfaces 25' are each in a single plane which extends through the surface 30 of the same side of straps 11''. In the form shown in Fig. 6 the end barrels are approximately square in cross-section, with the pintle openings 12'' extending through both end barrels. With the form shown in Fig. 6 the ordinary sprocket 14 can not be used, but a special sprocket must be provided so that there will be proper articulation between the driving teeth of the sprocket and the end barrels which are approximately square in cross-section. However, the form shown in Fig. 6 has the advantage that the wear of the chain will be reduced where it travels over the bottom plate 21 because of the larger area of contact between the bottom plate 21 and the faces of the block links which slide thereover, it being evident that one side of the chain slides over the bottom plate 21 and the other side of the chain slides over the wear plate 23 of the channel guide 22.

In an ordinary chain the side bars have a width greater than the diameters of the end barrels. If such a chain traveled along the wear plate 23 and moved laterally therefrom to a limited extent so the side bars at one side of

the chain run off the plate the barrels would be let down to the edge of the plate 23, and such action would result in undue wear at such ends of the barrels. This can easily be understood by assuming the chain of Fig. 1 traveling while upside down and observing that the semi-cylindrical portions 26 of the barrels 10 are spaced from the adjacent edges of the links 11 one of which rides on plate 23 and the other of which runs off the plate 23.

In fact the flat surfaces 25, 25 and 11', 11' all in a single plane distribute the wear so widely as to enable the flights 17, 17 to be substituted for the side bars 9. In that event the channel 22 and the wear plate may be no wider than the width of the block links 8, the latter being the only links then riding on the plate 23 except when the chain between pairs of flights 17, 17 bends laterally thereby carrying the lower edges of the side bars onto the plate 23.

In the form shown in Figs. 3, 4 and 5 and in the form shown in Fig. 6, internal recesses 31', 31' are provided for receiving lubricant for that portion of the pin or pintle 13 which extends through the openings 12 or 12'.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. A sprocket chain link having end barrels each semi-cylindrical on one side and having a flat bearing surface on the other side with a width approximately equal to the diameter of the barrel and adapted to bear on the slide over a flat supporting surface for the return run thereof.

2. A block link for sprocket chains comprising spaced end barrels connected by side straps with the barrels rounded on one side to engage sprocket teeth and flattened on the other side to form a bearing surface for engaging a flat guiding surface, such flat surface of each barrel extending over approximately the full width and length thereof.

3. A chain link comprising end barrels connected by side straps with the barrels provided with flat surfaces in a plane parallel to the direction of travel of the link and with flat rectangular leading and trailing rectangular surfaces extending transversely of the link.

4. A chain link comprising end barrels connected by side straps with each barrel provided with flat leading and trailing surfaces extending transversely of the link and a connecting flat

surface in a plane parallel to the direction of travel of the link.

5. An integral block link for sprocket chains comprising spaced apart end barrels connected by integral side straps with each barrel provided with leading and trailing flat rectangular surfaces extending transversely of the chain and connecting flat surfaces parallel to the direction of travel of the chain, such connecting flat surfaces being in a single plane which also coincides with flat surfaces on the straps, the construction being such that the flat surfaces are adapted to engage a plane guide of a width equal to the width of the link and remain in the same plane although shifted laterally from such guide to a limited extent.

6. A block link for sprocket chains comprising spaced-apart end barrels connected by side straps to form a rectangular opening between flat surfaces on one face of the link extending over approximately the full length of the link, each barrel having flat leading and trailing faces extending transversely of the link and connected by the aforesaid flat surfaces.

7. A rectangular integral block link having end barrels connected by integral side straps with openings extending transversely of the link through said barrels to receive hinge pins, said barrels being each semi-cylindrical on one face to engage the teeth of a sprocket and each provided on the other face with a flat surface in a single plane which also extends through flat faces on the side straps, and each of said barrels having flat rectangular leading and trailing faces extending transversely of the link and connecting the said semi-cylindrical surfaces to the flat surfaces, the distance between the end limits of the flat surfaces being equal approximately to the full length of the link.

8. A chain adapted to be driven by a sprocket and having a link formed of rigidly attached end barrels and side bars, and interconnecting means including interconnecting pins extending through apertures in said end barrels, said barrels and side bars having flat bearing surfaces lying in a single plane and adapted to bear on and slide over a supporting flat guideway during the return run of said chain, the bearing areas of said end barrels being as wide as the diameters of the interconnecting pins.

9. A chain adapted to be driven by a sprocket and having a link formed of rigidly attached end barrels and side bars, said barrels having chain connecting pin apertures therethrough and flat bearing surfaces lying in a single plane and adapted to bear on and slide over a supporting flat guideway during the return run of said chain, said flat bearing surfaces being as wide as the diameter of said apertures.

ROBERT E. BRIGGS.

CERTIFICATE OF CORRECTION.

Patent No. 2,286,666.

June 16, 1942.

ROBERT E. BRIGGS.

It is hereby certified that error appears in the printed specification of the above numbered patent requiring correction as follows: Page 2, first column, lines 5 to 8 inclusive, strike out "The width of each surface 25 is preferably substantially equal to the diameter of the barrel, and is generally at least as wide as the diameter of the pin 13 or pin opening 12.", and insert the same after the period and before "In", same page, second column, line 23; page 3, first column, line 40, for "the slide" read --and slide--; and that the said Letters Patent should be read with this correction therein that the same may conform to the record of the case in the Patent Office.

Signed and sealed this 11th day of August, A. D. 1942.

Henry Van Arsdale,

(Seal)

Acting Commissioner of Patents.
